LIGHT AND SHOULDER REST COMBINATION FOR A TELEPHONE HANDSET

Anthony Zacharia, Los Angeles County, Calif.
(5935 Colfax Ave., North Hollywood, Calif. 91601)

Filed Oct. 25, 1967, Ser. No. 9,164

Term of patent 14 years

(Cl. D26—14)

Ex. 1

Ex. 2

FIG. 3FIG. 4FIG. 5FIG. 6FIGURE 1 is a front perspective view of the light and shoulder rest combination showing my new design; FIGURE 2 is a rear perspective view thereof;

The showing of a telephone handset in broken lines in FIGURE 1 is for illustrative purposes as to the use of the invention.

I claim:

The ornamental design for a light and shoulder rest combination for a telephone handset, substantially as shown and described.
